UNITED STATES PATENT OFFICE.

PAUL BENDIX, OF NEW YORK, N. Y.

DESIGN FOR A PACKING-SHEET OF FIBROUS MATERIAL.

46,860.

Specification for Design.

Patented Jan. 19, 1915.

Application filed December 30, 1912. Serial No. 739,418. Term of patent 7 years.

To all whom it may concern:

Be it known that I, PAUL BENDIX, a citizen of the German Empire, residing at New York, in the county and State of New York, have invented a new, original, and ornamental Design for Packing-Sheets of Fibrous Material, of which the following is a specification, reference being had to the accompanying drawing, forming part thereof.

Figure 1 is an elevation and Fig. 2 an end view of a packing sheet of fibrous material, showing the new design.

The design relates to manufactures for packing purposes and consists of a series of square, bolster-like subdivisions, formed by intersecting twisted-cord-like elements, con-

necting small button-shaped elevations, located at the corners of the subdivisions.

I claim—

The ornamental design for a packing sheet of fibrous material, as shown and described.

In witness whereof I have hereunto set my hand in the presence of two subscribing witnesses, at New York, in the county and State of New York, this 23rd day of December, 1912.

PAUL BENDIX.

In presence of—

RALPH JULIAN SACHERS,
JOHN C. ZULEGER.
